UNITED STATES PATENT OFFICE.

HALLDOR K. HALLDORSON, OF EDINBURG, NORTH DAKOTA.

BELT THROWER AND GUIDE.

1,217,304.

Specification of Letters Patent. Patented Feb. 27, 1917.

Application filed May 17, 1916. Serial No. 98,130.

To all whom it may concern:

Be it known that I, HALLDOR K. HALLDORSON, a citizen of the United States, residing at Edinburg, in the county of Walsh, State 5 of North Dakota, have invented certain new and useful Improvements in Belt Throwers and Guides; and I do hereby declare the following to be a full, clear, and exact description of the invention, such as will enable 10 others skilled in the art to which it appertains to make and use the same.

This invention relates to a belt thrower and guide.

An object of the invention resides in the 15 provision of an improved structure by means of which a pulley belt may be readily thrown from the pulley or guided thereon during its operation.

A further object of the invention resides 20 in so constructing the device that the belt throwing arm will be doubly supported during its entire movement.

With these and other objects in view, such 25 as will appear as my description progresses, my invention comprises the combination and arrangement of parts as set forth in and falling within the scope of the appended claim.

In the drawing:

30 Figure 1 is a plan view of my device showing the same applied to an engine, only a portion of the latter being shown however;

Fig. 2 is a side elevation of the same;

35 Fig. 3 is an enlarged detail of the shifting arm and mounting therefor, and

Fig. 4 is a similar detail of the controlling lever.

In the drawing, I have illustrated conventionally an engine 1 which is provided with 40 a drive belt pulley 2.

In order that this belt which is indicated by the character 3 may be guided or thrown from the pulley 2, I have provided a bracket 4 which is secured to the engine casing by a 45 plurality of bolts 5 which pass through slots 6 therein. This bracket may thus be adjusted horizontally upon the loosening of the bolts and held in its adjusted position upon the tightening of the bolt. This casting is 50 provided with a downwardly extending arm 7 from which an integral plate 8 extends at right angles. Pivotally mounted, at 9, on this plate 8 is a shifting arm 10 which is provided with a roller 11 on its end and slides 55 upon the plate about its pivot. This arm is

guided in its movement by means of a guide rod 12 which is located in spaced relation to the plate 8 and is supported thereon by rivets 13 which limit the movement of the arm 10. The roller 11 is adapted to engage the edge of the belt 3 and in order that the arm may be moved so as to guide the belt on the pulley 2 or to throw it from the pulley, I have provided a casting 14 which is secured to the engine casing at a suitable 60 point and is provided with an arcuate slot 15. A lever 16 is pivoted, at 17, on this casting 14 and is provided with a set screw 18 which extends into the slot 15 and is adapted to be tightened to maintain the 65 lever in any of its adjusted positions. A rod 19 extends from this lever 16 and is secured to the arm 10 between its ends so that when the lever is moved the arm will be moved about its pivot. 75

It will be seen with this construction that the guide arm may operate to either throw the belt entirely from the pulley or to guide the same thereon. Furthermore it will be seen that the device is so constructed that 80 the guide arm will be strengthened and supported irrespective of its position.

While I have illustrated and described a particular embodiment of my invention, it has merely been for the sake of convenience 85 and I do not wish to be limited to that particular embodiment as it is obvious that numerous changes may be made in the details of construction without departing from the spirit of the invention or exceeding the scope 90 of the appended claim.

What I claim is:—

The combination with a belt and pulley, of a support, a bracket adjustably mounted on said support and movable in a plane parallel to the plane of the pulley, said bracket having a plate extending therefrom in angular relation, a shifting arm pivotally mounted on the plate remote from the edge thereof and resting upon the plate, a guide 100 for the arm disposed on the plate and above the arm, a roller on the end of the arm and means for moving the arm pivotally to and away from the pulley. 95

In testimony whereof, I affix my signature, in the presence of two witnesses.

HALLDOR K. HALLDORSON.

Witnesses:

E. A. BRANDSON,
S. JOSEPHSON.
